Augustus M. Henry

UNITED STATES PATENT OFFICE

THOMAS H. MCCLAIN, OF CLIFFSIDE PARK, NEW JERSEY, ASSIGNOR TO ROY G. MAC-PHERSON, OF FRAMINGHAM, MASSACHUSETTS

SOUND-REPRODUCING DEVICE

Application filed January 21, 1928. Serial No. 248,276.

This invention relates to an improvement in sound reproducing devices and has for its object to produce an electroresponsive device which may be either electrodynamic or electromagnetic or of any other type which will be so designed that it will act to transform any mechanical vibration into a plurality of independent or divided sources of electrical energy.

10 Heretofore, particularly in phonograph reproducing systems of the electrical type, it has been the common practice to transform the mechanical vibrations received from the record into a single electrical channel, covering all the audio frequencies, regulating merely this single channel of frequencies as desired to secure the best tone quality, or at least the tone quality most generally found satisfactory by the majority of listeners. It 15 has been found in practice that this regulation of the entire band or channel of audio frequencies extending generally from 100 to 7000 cycles as a unit, is inadequate to properly produce the final tonal quality desired 20 by the musically fastidious. In some instances where this is done, harsher notes are emphasized to the detriment of sweeter or purer tones; in other instances, where regulation by filtration is attempted, desirable frequencies 25 are cut off and an unnatural tone results. Thus, there have been for some time past, efforts made to regulate tonal quality by suppression of undesirable frequencies in the tonal register, but in all instances, such efforts 30 have proved inadequate due to the fact that they were usually made at the output of the amplifying device, or else at the output of the "pick-up" device, and in all instances, were made by operation upon the entire band 35 of audio frequencies constituting the entire scale of reproduction of the "pick-up" device employed.

The object therefore, of this invention is to provide a sound reproducing device particularly adapted for reproduction of phonograph or like records which will, as was heretofore mentioned, transform the mechanical vibrations into a plurality of independent or divided sources of electrical energy, such 45 sources constituting separate audio fre-

quency bands or channels. Through such an arrangement as this a very wide degree of control or adjustment may be exercised over the various frequency bands thus rendering the final tonal output of the device as "pure" 55 and satisfactory as may be required by different listeners.

With these objects and such other objects as may hereinafter appear, in view, I have devised the particular arrangement of parts 60 hereinafter set forth, and more particularly pointed out in the claims appended hereto.

Reference is to be had to the accompanying drawing, in which the figure shown is a diagrammatic view illustrating the application 65 of my device.

In the arrangement shown, 1 indicates diagrammatically a conventional form of "pick-up" device used for the electrical reproduction of phonograph records. The same may 70 be of the electrodynamic or of the electromagnetic type, and is provided with the usual armature 2, which carries the stylus 3 in any of the conventional ways. The stylus 3 moves in the record grooves as is usual in this type 75 of device.

At 4 is shown a coil which is shown surrounding the armature and at 5 is shown another coil which may if desired be superimposed or wound over the coil 4. These coils 80 are so designed and arranged that they operate at highest efficiency under particular bands of frequency. For the purposes of illustration, we might assume that the coil 4 has its highest operating efficiency or frequencies extending from 0 to 2500 cycles and the coil 5 operates most efficiently on a band extending from 2000 to 10,000 cycles. Thus, through the arrangement described, the range 85 of frequencies, extending it the utmost from 0 to 10,000 frequencies is divided into several separated bands which may be controlled independently of one another or separately amplified as required.

The coil 4 has its ends 6 and 7 connected to the primary of an audio transformer 8 and extending across the output leads 9 and 10 of said audio transformer is a variable resistance or potentiometer 11 which may be used 90 for varying the strength of the output signal. 95

nals from the audio transformer 8. A sound amplifier or loud speaker 18 is placed in circuit with the output of the audio transformer 8.

5 The coil 5 has its ends 12 and 13 connected to the primary of an audio transformer 14 which may be similar to the audio transformer 8. The output leads 15 and 16 of the audio transformer 14 are connected by a variable resistance or potentiometer 17.

10 From the foregoing, the operation of my improved sound reproducing device will be readily understood. A second sound amplifier or loud speaker 19 is placed in circuit 15 with the output of the other audio transformer 14. Assuming that the coil 4 operates on the low frequencies extending from 0 to 2500 cycles. This band of frequencies can be controlled as to volume or otherwise through the 20 resistance 11 or any other similar controlling means. The other coil 5 operating on a band of frequencies extending from 2000 to 10,000 cycles is likewise independently controllable or regulatable by its own particular resistance 25 17.

30 The two channels thus described may be separately amplified by independent amplifiers of similar or of different characteristics and thereafter may be connected to separate reproducers or loud speakers. They may also be joined beyond their amplifiers and thence connected to a single speaker. If preferred, they can be joined to a single amplifier and many other arrangements may be made without departing from the scope of 35 my invention.

40 Additionally while I have shown and described the utilization of two coils, it will be obvious that as many coils as may be required dividing the band of frequencies up into separate channels may be utilized.

45 With respect to the particular type of coils employed, I state that these may be arranged in any suitable manner dictated by proper constructional methods. The coils may be superimposed or they may be positioned in any other way. The coils in one type of unit may be placed on the armature or they may be placed and used as field coils in other 50 types.

55 It is also possible to place and use such coils as oscillator coils placed externally of the actual pick-up, particularly in the case where the pick-up employed is of the condenser or carbon type or in connection with a microphone.

60 Having described my invention as being particularly applicable for the reproduction of mechanical impulses and the transformation 65 of such impulses into electrical energy such as is done in phonographic reproduction, I do not however, limit myself to this particular employment of my invention as the same may be used in other ways and for other purposes.

It is also possible to reverse the use of the construction described so that phonograph records may be produced from this construction rather than reproduced in sound.

70 It will be seen from the construction and method of operation described that a great range of control is afforded by my invention and the tonal quality and volume of various notes in the register is easily regulatable. Thus, when bass notes are desired, the channel covering the lower band of frequencies is 75 regulated so that these notes are pronounced. The same is true of any of the other channels of frequencies since the same are divided and easily regulatable as was heretofore pointed out.

80 Having described one embodiment of my invention, it is obvious that the same is not to be restricted thereto but is broad enough to cover all structures coming within the 85 scope of the annexed claims.

What I claim is:

1. An electroresponsive device comprising an electro-magnetic phonograph "pick-up" device, inductances associated therewith, 90 said inductances being separately efficient on different bands of sound frequency, said inductances having separate outputs, and separate controlling means for regulation of the outputs of said coils.

2. An electrical reproducer for phonographs comprising an electromagnetic pick-up device having a plurality of electromagnetic pick-up coils, audio amplifiers associated with said coils, and loudspeakers connected to said amplifiers. 100

3. An electric reproducer for phonographs comprising an electromagnetic pick-up device having a plurality of electromagnetic pick-up coils, reproducing means having a corresponding number of energizing coils, and an audio amplifier connecting each pick-up coil with each energizing coil. 105

4. An electrical reproducer for phonographs comprising an electromagnetic pick-up device having a plurality of electromagnetic pick-up coils, reproducing means having a corresponding number of energizing coils, and audio amplifiers connecting the respective pick-up and energizing coils and tuned to resonance at different frequencies in the audio range. 115

5. An electrical reproducer for phonographs comprising an electromagnetic pick-up device having a vibrating armature and a plurality of electromagnetic pick-up coils, reproducing means having a corresponding number of energizing coils, and an audio amplifier connecting each pick-up coil with each energizing coil. 120

6. An electric reproducer for phonographs comprising an electromagnetic pick-up device having a plurality of electromagnetic pick-up coils, audio amplifiers associated with 125 each energizing coil.

said coils, and loudspeakers connected to said amplifiers.

7. An electrical reproducer for phonographs comprising a plurality of electromagnetic pick-up coils, a common armature for said coils, reproducing means having units including energizing elements equal in number to the pick-up coils, and audio amplifiers connecting the respective pick-up coils and 10 energizing elements and tuned to different frequency ranges.

8. An electric reproducer for phonographs comprising a plurality of electromagnetic pick-up coils, a common armature for said 15 coils, loud speakers and an audio amplifying system connecting said pick-up coils and loud speakers.

Signed at the city, county, and State of New York this 20th day of January, 1928.
